A. E. HAGUE

AUTOMATIC ELECTRIC CUT-OUT

Filed Feb. 27, 1926

Inventor:
Alfred E. Hague.
by J. G. Roberts Atty.

UNITED STATES PATENT OFFICE.

ALFRED E. HAGUE, OF EAST ORANGE, NEW JERSEY, ASSIGNOR TO WESTERN ELECTRIC COMPANY, INCORPORATED, OF NEW YORK, N. Y., A CORPORATION OF NEW YORK.

AUTOMATIC ELECTRIC CUT-OUT.

Application filed February 27, 1926. Serial No. 91,189.

This invention relates to telephone exchange systems and more particularly to such systems wherein automatic switches are employed for establishing connections.

5 In electrical systems it is customary to connect the battery supply to the apparatus under the control of current limiting devices such as fuses which open the circuit in the case of an unusual increase in current due to any cause. In the case of machine switching telephone systems the apparatus constituting a switching unit is usually connected to battery through a single fuse. The "blowing" of such a fuse has long been employed 10 to cause an alarm to be sounded. However, this alarm does not prevent the selection of the apparatus unit and the consequent failure of the attempted connection.

The object of the present invention is the 20 automatic removal of an apparatus unit from service in response to unstandard conditions.

A feature of the invention lies in means 25 responsive to such an overload as would operate a current limiting device to render busy the apparatus fed therethrough.

A more particular feature of the invention lies in providing an extra winding on the 30 relay which normally renders the apparatus unit busy, each terminal of said winding being connected to battery through a separate current limiting device.

It results from the above arrangement that when any part of the battery feed of 35 an apparatus unit is overloaded, the relay mentioned is operated and locked to render the apparatus unit busy until the battery feed and current limiting device have been restored to normal. Where the apparatus units are arranged serially, the unit on which the overload occurs is automatically removed 40 from the series and the control circuits extended to the next unit.

The arrangement of the invention may be 45 applied to any type of system but was particularly developed for use in connection with an automatic private branch exchange of the type disclosed in the application of W. P. Albert, Serial No. 698,635, filed 50 March 12, 1924, patented April 13, 1926, No. 1,580,630. It is of especial value in such a system since a private branch exchange would probably be dependent for mainte-

nance on outside service and serious delays 55 might result from the blowing of a fuse.

The drawing shows the method of applying the invention to two types of circuit. The arrangement shown below the broken line is typical of a "gang" start arrangement; the arrangement shown above the 60 broken line is a skeletonized arrangement similar to that employed in the link and trunk circuits of the above identified applications.

An example of the type of circuit shown 65 below the broken line is the coin circuit disclosed in Fig. 13 of U. S. application of I. H. Henry, Serial No. 743,920, filed October 16, 1924, patented March 9, 1926, No. 1,575,836. From a consideration of that application it 70 will be seen that, when one of the coin circuits is to be employed, ground is connected to the common start lead and over the back contact of relay 1314 to the power magnet of the switch associated therewith. Similar 75 circuits are completed for each idle coin circuit. When a coin circuit is associated with the selector circuit, relay 1314 is operated to stop the switch and remains operated throughout the use of the coin circuit, thus 80 rendering the circuit busy.

Relays 1314—A, 1314—B, 1314—C, etc., shown in the drawing represent a relay, such as relay 1314 of the above mentioned application, individual to each of a number of 85 coin circuits. The connection of ground to start lead 101 completes a circuit (not completely shown) over the back contact of each relay 1314—A, 1314—B etc. for the power magnets of the corresponding switches. The 90 operation of one of said relays prevents the completion of said circuit to the corresponding magnet. All the apparatus of the switching unit associated with relay 1314—A, for example, is fed through fuse 95 102; all that associated with relay 1314—B is fed through fuse 103 and all that associated with relay 1314—C through fuse 104. An auxiliary winding is provided for each 100 of these relays one side of which is connected to battery through the group fuses 102, 103, 104 etc. The other terminal of each winding is also connected to battery through a fuse. To avoid the removing of 105 the entire number of apparatus units from service at one time, should the second termi-

nal of the relay be grounded, they are divided into two groups. The auxiliary winding of all the relays of one group is connected to battery through fuse 105 and of all of the other group through fuse 106.

Should any part of the battery feed conductor 112 be grounded directly, it would result in "blowing" fuse 102. This same ground would complete a circuit from battery over bus bar 150 through fuse 105, left winding of relay 1314-A, to this ground.

Relay 1314-A when locked to ground through resistance 122 will remain locked until the ground has been removed and the fuse 102 replaced, at which time the current through the left winding is reduced sufficiently to permit the relay to release. The operation of relay 1314-A would open the circuit of the corresponding power magnet and render the unit busy. The auxiliary winding is sufficiently marginal to be unaffected by operating grounds through relays etc.

The operation in case an excessively high voltage were applied to conductor 112 would be the same. If battery or excessive voltage were applied to the special battery feed 107, half of the units would be removed from service.

30 The blowing of any of the fuses releases a link (not shown) to connect bus bars 150 and 140. This link completes a circuit to ground through relay 141. Relay 141 in operating closes a circuit for lamp 142 and buzzer 143, providing both a visual and an audible signal that a fuse has been blown. One or both of these signals may conveniently be located at the central office.

40 The arrangement shown above the broken line shows the application of the invention to the system disclosed in the above mentioned Albert application. Relay 201 represents the line relay of that disclosure. Relays 205-A, 205-B, 205-C, etc., represent the start relays of a plurality of link circuits. Relays 204-A, 204-B, 204-C, etc. represent the transfer relays of the corresponding link circuits. It is obvious that the operation of relay 201 will cause the operation of relay 205-A if relay 204-A is not operated and that the operation of each of the relays 204-A, 204-B or 204-C transfers the start circuit controlled by relay 201 to the start circuit of the next link circuit. From a consideration of the above mentioned Albert application it will be seen that the relay 204 of the link circuit is operated as soon as the calling line has been connected through to that link circuit transferring the start circuit to the next link circuit.

45 As in the case of relay 1314-A, etc., relay 204-A has been provided with a second winding, one side of which is connected to battery through fuse 151, which fuse feeds

battery to the apparatus of the corresponding link circuit, and the other side of which is connected to battery through fuse 154, which is common to one half the relays 204-A, etc. Since battery potential is the same on each side of the winding, there will be no current drain therethrough. If the feed lead of any link circuit such as lead 156 is grounded or crossed with a high voltage, the associated relay 204-A will be operated and will lock through resistance 157 to ground, thus transferring the start circuit to the next link.

50 That the invention is particularly advantageous in an arrangement of this sort may be readily seen. Suppose, for example, that relay 205-A were, as shown, the first relay to which the start lead is extended. If fuse 151 should be blown, neither relay 205-A nor relay 204-A could operate and the entire system would be out of service until the fuse is replaced.

55 The operation of the alarm circuit 145 would be the same in this case as above described.

60 What is claimed is:

1. In a telephone exchange system, a plurality of switches, means in each switch for normally rendering said switch busy, separate means for supplying the apparatus of each switch with battery, and means responsive to an unstandard condition of said battery supply means to operate said busying means.

65 2. In a telephone exchange system, a plurality of switching units, means supplying battery to the apparatus of a switching unit under the control of a current limiting device responsive to an unstandard condition of said battery supply means, and means also responsive to an unstandard condition of said battery supply means to remove said switching unit from service.

70 3. In a telephone exchange system, a plurality of switching units, means in each switching unit for normally rendering said switching unit busy, means for supplying the apparatus of each switching unit with battery under the control of a current limiting device responsive to an unstandard condition of said battery supply means and means also responsive to an unstandard condition of said battery supply means to operate said busying means.

75 4. In a telephone exchange system, a plurality of switching units, means in each of said switching units including a relay for normally rendering said switching unit busy, means for supplying the apparatus of each switching unit with battery under the control of a current limiting device individual to said unit and responsive to an unstandard condition of said battery supply means, an auxiliary winding for said busying relay, and means also effective in the

presence of an unstandard condition to energize said relay through said auxiliary winding.

5. In a telephone exchange system, a plurality of switching units, means for supplying battery to the apparatus of each switching unit under the control of a current limiting device, and means responsive to the presence of an unstandard condition which 10 would operate said current limiting device to also remove said switching unit from service.

6. In a telephone exchange system, a plurality of switching units, means in each 15 switching unit for normally rendering said switching unit busy, means for supplying the apparatus of each switching unit with battery under the control of a current limiting device individual to said unit, and 20 means responsive to the presence of an unstandard condition which would operate said current limiting device to operate said busying means.

7. In a telephone exchange system, a plurality of switching units, means for supplying battery to the apparatus in each switching unit through a fuse, and means for employing an unstandard condition that would 30 open said fuse to removed said switching unit from service.

8. In a telephone exchange system, a plurality of switching units, means in each switching unit for normally rendering said switching unit busy, means for supplying 35 the apparatus of each switching unit with battery through a fuse individual to said unit, and means responsive to the presence of an unstandard condition which would open said fuse to operate said busying 40 means.

9. In a telephone exchange system, a plurality of switching units, means in each of said switching units including a relay for normally rendering said switching units 45 busy, means for supplying the apparatus of each switching unit with battery through a fuse individual to said unit, and means responsive to the presence of an unstandard condition which would open said fuse to operate said busying relay.

10. In a telephone exchange system, a plurality of switching units, means in each of said switching units including a relay for normally rendering said switching unit 55 busy, means for supplying the apparatus of

each switching unit with battery through a fuse individual to said unit, an auxiliary winding for said busying relay, and means responsive to the presence of an unstandard condition which would open the fuse to energize said relay through said auxiliary winding.

11. In a telephone exchange system, a plurality of switching units, means in each of said switching units including a relay for 60 normally rendering said switching unit busy, means for supplying the apparatus of each switching unit with battery through a fuse individual to said unit, an auxiliary winding for said busying relay, means responsive to the presence of an unstandard condition which would open said fuse to energize said relay through said auxiliary winding, and means to hold said relay operated until said unstandard condition has 75 been removed.

12. In a telephone exchange system, a plurality of switching units, means in each of said switching units including a relay for 80 normally rendering said switching unit busy, means for supplying the apparatus of each switching unit with battery through a fuse individual to said unit, an auxiliary winding on said busying relay each terminal of which is connected to battery through 85 a separate fuse whereby the presence of an unstandard condition which would open said fuse will energize said relay through said auxiliary winding to render said switching unit busy.

13. In a telephone exchange system, a plurality of switching units, means in each of said switching units including a relay for normally rendering said switching unit busy, means for supplying the apparatus of 90 each switching unit with battery through a fuse individual to said unit, an auxiliary winding on said busying relay each terminal of which is connected to battery through a separate fuse whereby the presence of an 100 unstandard condition which would open said fuse will energize said relay through said auxiliary winding to render said switching unit busy, and means to hold said relay operated until said unstandard condition has been removed.

In witness whereof, I hereunto subscribe my name this 26th day of February A. D., 1926.

ALFRED E. HAGUE.
